UNITED STATES PATENT OFFICE.

JOHN L. MAY, OF MARTINSBURG, PENNSYLVANIA.

RECLINING-CHAIR.

SPECIFICATION forming part of Letters Patent No. 349,508, dated September 21, 1886.

Application filed February 4, 1884. Serial No. 119,734. (No model.)

To all whom it may concern:

Be it known that I, JOHN L. MAY, a citizen of the United States, residing at Martinsburg, in the county of Blair and State of Pennsylvania, have invented certain new and useful Improvements in Invalid-Chairs; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a side view of my chair. Fig. 2 is a vertical sectional view of the same. Fig. 3 is a plan view. Fig. 4 is a vertical sectional view. Fig. 5 is a side view, chair folded; and Fig. 6 is a detail view.

This invention has relation to adjustable invalid or folding chairs; and it consists in the construction and novel arrangement of devices, all as hereinafter set forth, and particularly pointed out in the claims appended.

In the accompanying drawings, the letter A designates the rectangular horizontal frame of the chair-seat, the bars of which are firmly secured to the legs B, which are braced together by rounds C.

D D represent quadrant-racks having teeth a upon their concave edges. These racks are laterally arranged under the seat, being respectively secured by their upper ends to the side bars, b, of the seat-frame, and by their lower ends to the side rounds, c. The seat-frame does not extend back between the upper portions of the rear legs of the chair, these legs being connected by a transverse bar, d, which is arranged at a lower level, and is provided with hinges e, which are also attached to the middle portion of the lower section, E, of the chair-back. The upper end of the back-section E is, when in upright position, about level with the arms F of the chair.

G represents the upper back-section, the side bars, f, of which are abutted against the side bars, g, of the lower section, E, as shown; and strong cross-bars h and k are provided connecting the side bars of the upper and lower section at the joint. Inside hinges l connect the upper and lower sections, and the side and cross-bars of said sections when abutted against

each other form a stop-joint, so that when the upper section is thrown back it is held firmly. Hooks m serve to connect the upper and lower sections at the back when necessary. The upper section may be folded forward on the arms when the chair is not required for use or is being transported. To the lower end of the lower section is pivoted a swinging transverse pawl-plate, Z', adapted to engage both of the quadrant-racks D D at the same time. The back may be adjusted at any angle of inclination within the compass of the racks, and will be held firmly in that position; or it may be thrown entirely back on a level with the seat to form a bed-bottom when the leg-rest is raised to the same level. In this position the back is designed to be supported by a prop-frame, H, which is pivoted to the upper section of the back in rear, and may be folded against the same when not in use.

The leg-rest K consists of a broad rectangular frame of the full width of the seat-frame, and hinged to the legs or main frame, as at n, these hinges being applied to the under side of the leg-frame and below the level of the seat-frame, so that when the leg-frame is raised its surface will be level with that of the seat. To the side bars, P, of the leg-rest are secured the forward ends of the quadrant-racks L L, which extend back on each side through slots or ways r r of the legs into the space, below the seat. To the front legs and in front thereof is hinged a swinging pawl-plate, N, which extends transversely of the frame, and is adapted to engage the teeth of both of the quadrant-racks L L at the same time after adjustment of the leg-rest, holding the same firmly at the desired angular inclination.

To the rear portions of the side bars, v, of the seat-frame are pivoted the upper ends of arms V, which are parallel to the leg-rest, and are connected thereto by the horizontal bars Z, which are hinged to the arms V at s, and are pivoted to the side bars of the leg-rest at t. The forward ends of the low horizontal bars z project, as at v, and to these projections are pivoted the projections or arms w of the transverse foot-rest W, which is a broad rocking bar having lateral extensions a', which rest on the forward extensions of the horizontal bars Z, as shown.

I am aware that it is not new to provide a

chair with a hinged back carrying a quadrant to engage a rod in the main frame, the said chair having a hinged foot-rest which carries a slotted toothed segment adapted to be adjusted at any desired point with relation to the seat portion of the main frame. I am also aware that a chair-frame has been provided with a pivoted foot-rest, a pivoted section arranged intermediate of the seat and foot-rest, 10 and carrying a toothed segment engaging the main frame, and a hinged back having its arms carrying pawls, which engage racks secured to the main or seat frame, and therefore do not claim any of these devices, broadly; but,

15 Having described this invention, what I claim, and desire to secure by Letters Patent, is—

1. In a chair, the combination, with the seat-frame, constructed as described, of the back 20 composed of the lower section, E, hinged below the level of the seat, and the upper section, G, hinged to the upper end of the lower

section, the prop pivoted to the back of the said upper section, and the lower end of the lower back-section having suitable means for locking the back in different inclined positions, substantially as specified.

2. In a chair, the combination, with the main frame, of the hinged leg-rest K, the quadrants secured thereto and working in slots of the front legs, the transverse pawl-plate hinged to the said legs to engage the quadrants, the arms V, pivoted at their upper ends to the lateral seat-beams, and the bars Z, pivoted at their outer ends to the leg-rest and hinged at their inner ends to the lower ends of the arms V, substantially as specified.

In testimony whereof I affix my signature in presence of two witnesses.

JOHN L. MAY.
